UNITED STATES PATENT OFFICE

2,177,844

TELEPHONE BOOTH SPACER

Percival H. Sherron, Jamaica, N. Y.

Application January 26, 1937, Serial No. 122,364

2 Claims. (Cl. 189—34)

This invention relates to a telephone booth spacer designed to space adjoining telephone booths arranged side by side in series and to close or cover the gap between such adjoining booths.

5 In arranging the installation of a series of public telephone booths it is customary to place the booths side by side, but I have found it, however, generally undesirable, for adequate sound insulation, to have the walls of adjoining booths actually contact each other. If the adjoining booths be merely slightly separated, however, the spacing is apt to be non-uniform, and the space between the booths tends to collect dust and debris and to present a generally unsightly appearance.

10 15 In my copending application, Serial No. 120,322, filed January 13, 1937, I have described and claimed an improved metal telephone booth. The present invention is particularly directed to the installation of such booths in series or banks, and involves a specially designed member adapted to close the opening or space left between the walls of adjoining booths.

20 25 The accompanying drawings show a preferred embodiment of my invention, which will accordingly be described with reference thereto. In the drawings:

Fig. 1 is a perspective view of a single telephone booth of the type shown in my said application Serial No. 120,322, filed January 13, 1937.

30 Fig. 2 is fragmentary front elevation showing two booths of the type shown in Fig. 1 positioned side by side with my spacing member in place between them.

Fig. 3 is a plan view, also fragmentary, of the 35 adjoining booths shown in Fig. 2.

Fig. 4 is a cross-section through the body of my spacing member.

Fig. 5 is a section on the line 5—5 in Fig. 2.

And Fig. 6 is a section on the line 6—6 in Fig. 2.

40 The telephone booth 1 has an outer wall 3, preferably of one piece, open at the front to form a doorway bounded by door jambs 5 and closed by a folding door 7. A baseboard 9 formed by a flange on the floor assembly 11 is welded to the lower edge of the outer face of wall 3.

45 The spacer member 13 is formed preferably of metal matching the booth and has a body portion 15, shown in cross-section in Fig. 4, which extends from the upper edge of the baseboard 9 to the top of the booth wall 3, which, as shown in Fig. 2, extends somewhat above the level of the roof 17. The body portion 15 of the spacer member comprises a plate 19, embossed with a central

longitudinal rib 21, and bent back upon itself at 23. Flanges 25 integral with the body extend outwardly, in normally divergent paths, from the portions 23.

Extending downward from the body portion 15 5 of the spacer for a distance equal to the height of baseboard 9 is skirt portion 27 of the spacer member, in which the plate 19 and rib 21 are continued, but portions 23 and flanges 25 are omitted. Machine screws 29, receivable in tapped 10 holes in the baseboard 9 and jamb 5 of each booth, serve to secure the skirt 27 to the booths.

At the upper end of the spacer 13 the material forming flanges 25 is continued upwardly above the upper end of plate 19 and bent over upon it- 15 self to form hook-like straps 31.

In arranging the telephone booths in series or banks in accordance with my invention the booths are positioned side by side with the walls of adjoining booths spaced a distance $a-a$, determined 20 by the width of the spacer 13 at $b-b$. The spacer 13 is then slipped into place between the booths with the flanges 25 sprung into the opening between the booth walls to frictionally engage the same by reason of their resiliency, and the hook- 25 straps 31 are engaged with the upper edges of the walls 3. Skirt 27 of the spacer is then secured to the booths by means of screws 29, and the entire space between the adjacent booths is thus closed by the member 13. 30

What I claim and desire to protect by Letters Patent is:

1. A spacer for covering and concealing the space between spaced apart side walls of adjacent telephone booths comprising a front-plate 35 extending vertically when in normal use and a pair of rearwardly and outwardly extending flanges resiliently connected to said front-plate and extending from a point adjacent the bottom to above the top thereof, those portions of said flanges extending above the top of the front-plate being bent upon themselves about a horizontal axis to form a pair of hook-like members.

2. A spacer for covering and concealing the space between spaced apart side walls of adjacent telephone booths comprising a body portion having a front-plate extending vertically when in normal use and a pair of rearwardly and outwardly extending flanges resiliently connected to said front-plate and a flangeless skirt portion 50 forming a continuation of said front plate and extending below the body portion.

PERCIVAL H. SHERRON.
